Inventor:
Max G. Rosenthal,
By Robert Burns, Attorney.

UNITED STATES PATENT OFFICE

MAX G. ROSENTHAL, OF CHICAGO, ILLINOIS

ROTARY PUMP AND THE LIKE

Application filed September 18, 1928. Serial No. 308,793.

This invention relates to that type of rotary motors, pumps, meters and the like, in which the rotor member carries a series of sliding piston blades, adapted for sliding contact with the inner face of the eccentrically disposed chamber of the stator member of the appliance, an example of which is shown in my prior Patent No. 1,569,306, dated January 12, 1926, and this improvement has for its object.

To provide a structural formation and combination of parts in the above mentioned type of rotary apparatus, by means of which a durable and efficient fluid tight joint is maintained between the contact ends of the radial piston blades of the rotor member in their eccentric travel around and in contact with the closed bore or chamber of the stator member, all as will hereinafter more fully appear.

In the accompanying drawing:—

Fig. 1, is a transverse section of a rotary pump or the like apparatus embodying the preferred form of the invention.

Fig. 2, is a fragmentary horizontal section of same, on line 2—2 Fig. 1.

Fig. 3, is a fragmentary sectional elevation of the central portion of a pump or like apparatus illustrating a modified construction of parts.

Like reference numerals indicate like parts in the different views.

In the construction shown, the stator member 1 is of any usual form, having central piston chamber, approximately circular in cross section for the greater portion of its extent, with such portion merged into a segmental portion of less extent and in which the rotor member has bearing.

In addition said stator member is formed with passages 2 and 3, for the inlet and outlet of fluid to and from its piston chamber, and is also provided with closure heads 4, for the respective ends of such piston chamber.

The rotor member 5, of the usual cylindrical form, is arranged eccentrically in the piston chamber of the stator member 1, and in close contact with the above described segmental portion of said piston chamber. In addition the rotor member is formed with a

plurality of substantially radial recesses 6, for the reception and movement of the piston members of the structure. The construction so far described in common to the present class of rotary pumps and the like, and is fully disclosed in my aforesaid Patent No. 1,569,306.

The novel and material feature of this improvement involves a specific formation of the outer and bearing ends of the piston blades of a structure such as above described, and by means of which a close and durable bearing contact between the outer ends of the piston blades and the inner circular face of the piston chamber of the stator member 1 is attained in a simple and effective manner. To such end the invention involves broadly, the formation of the outer end of each piston blade by a plurality of thin plates 7, loosely associated together in side by side relation, and slidably arranged in the outer portion of an aforesaid radial recess 6 of the rotor member 5 and having a length equal to that of said rotor member.

Each plurality of thin plates 7 above described are capable of independent sliding movement, one upon the other, in order that their outer ends may move to and maintain close contact with curved surface of the piston chamber of stator member, in the eccentric relation of said piston chamber to the rotor member and the piston blades carried thereby. To such end the inner ends of each plurality of thin plates 7 will have support or abutment on a rocker member 8, the bearing face of which has a curvature of a radius substantially the same as the circular inner wall of the piston chamber. The rocker member 8 is in turn pivotally mounted on a spring 9, the tendency of which is to move the rocker member outwardly and maintain the plurality of thin plates 7 in close operative contact with the inner face of the piston chamber; the rocker member 8, being adapted to have a rocking movement on the spring 9, to permit of an independent sliding movement between the plurality of thin plates 7 as they maintain the required continued contact of their outer ends with the curved surface of the piston chamber, under the stress of the

spring 9. For heavy duty, the plurality of plates 7, associated rocker 8 and spring 9 are preferably arranged in a holder 10 of a channel shape in cross section, moving in a radial recess 6 of the rotor member, with each holder 10 provided with track rollers 11 at their respective ends for engagement in cam grooves 12 in the end heads 4 of the stator member.

10 The aforesaid cam grooves 11 will have a shape corresponding to the shape of the inner curved surface of piston chamber of the stator member 1, as set forth in my prior Patent No. 1,569,306, above referred to.

15 For light duty the entire sliding movement of the plurality of thin plates 7 and their supporting rocker 8, may be effected wholly by the spring 9 upon which said rocker is pivotally mounted. In such construction, each 20 rocker 8 will be pivotally mounted on a sliding plug 13 with a single spring 9 interposed between the ends of a diametrically opposed pair of the plugs 13 associated rockers 8 and pluralities of plates 7, as illustrated in Fig. 3.

25 I claim as my invention:

1. In a rotary pump or motor of the radially moving type of piston, the combination of a stator having a circular piston chamber, a rotor having a recess extending its entire length, a piston blade associated with said recess and comprising a plurality of thin plates in close sliding contact one with the other, and a rocker member forming a common bearing for the inner ends of said plates, the bearing face of said rocker member having a curvature the same as the curvature of the inner wall of the piston chamber of the stator.

2. In a rotary pump or motor of the radially moving piston type, the combination of a stator having a circular piston chamber, a rotor having a recess extending its entire length, a piston blade associated with said recess and comprising a plurality of thin plates in close sliding contact one with the other, a rocker member forming a common bearing for the inner ends of said plates, the bearing face of said rocker member having a curvature the same as the curvature for the inner wall of the piston chamber of the stator, and a spring forming a yielding abutment for said rocker member.

3. In a rotary pump or motor of the radially moving piston type, the combination of a stator having a circular piston chamber, a rotor having a recess extending its entire length, a piston blade associated with said recess and comprising a plurality of thin plates in close sliding contact one with the other, a rocker member forming a common bearing for the inner ends of said plates, the bearing face of said rocker member having a curvature the same as the curvature of the inner walls of the piston chamber of the stator, and a holder of a channel form and adapt-

ed to contain said plurality of plates and rocker member.

In testimony whereof I hereunto affix my signature.

MAX G. ROSENTHAL.
